UNITED STATES PATENT OFFICE

EDWIN W. NORTH, OF ROCKFORD, ILLINOIS, ASSIGNOR TO NATIONAL LOCK CO., OF ROCKFORD, ILLINOIS, A CORPORATION OF DELAWARE

FURNITURE TRIMMING

Application filed April 13, 1931. Serial No. 529,755.

This invention relates to trimmings such as knobs and pendants to be applied to furniture and more particularly to such a fitting as will eliminate the necessity of screws or 5 bolts for securing them to the furniture.

It has been the practice heretofore to secure trimmings of this nature to the fronts or other parts of furniture by means of screws or bolts. Securing means of this 10 character, however, are prone to become loose during use due to partial turning movements of the fittings and when once loosened the holes and securing means become worn after which it is practically impossible to maintain 15 the fittings in tight engagement with the furniture. Furthermore, when bolts or through screws are employed, the heads or nuts, as the case may be, constitute projections upon the inner side of the furniture 20 and are therefore objectionable.

It is the purpose of this invention to provide a trimming which may be permanently secured to the furniture without the use of 25 screws or the like by an anchorage means which eliminates any possibility of even partial turning of the trim and by means of which perfect alignment of the fittings may be assured.

According to this invention a fitting such as a knob or pendant is provided with an 30 expansible portion which is adapted to be received in a recess formed in the furniture and have a portion thereof deflected outwardly into the walls of the recess by an anvil-like member. In the preferred form, the 35 anvil-like member also serves the purpose of preventing turning movements of the trimming and is provided with means to prevent its sinking into the furniture whereby the trimming may be applied equally well to soft or hard wood. The trimming is preferably provided with a tubular post which 40 is formed with means thereon to prevent any pendants swivelled thereto from striking the furniture and with a projecting portion adapted to be received in a recess in the furniture to be engaged by the expanding anvil-like member. Where it is desired a spring 45 is also employed between the post and any

pendant swivelled thereto to prevent the pendant from rattling.

A better understanding of this invention will be had from the detailed description given in connection with the drawing, in 55 which:

Fig. 1 is a front elevation of a knob constructed in accordance with this invention.

Fig. 2 is a transverse section through approximately the center of the knob shown 60 in Fig. 1.

Fig. 3 is a section through a portion of an article of furniture showing the preparation thereof and the anvil member in position.

Fig. 4 is a perspective of the anvil element. 65

Fig. 5 is a section through a piece of furniture illustrating a knob constructed in accordance with this invention attached thereto.

Fig. 6 is a perspective of the post element of the trim. 70

Fig. 7 is a section on line 7—7 of Fig. 2.

Fig. 8 is a front elevation of a ring type trim embodying the principles of this invention.

Fig. 9 is a side elevation of the trim shown 75 in Fig. 8.

Fig. 10 is a front elevation of the pendant type trim embodying the principles of this invention.

Fig. 11 is a side elevation of the trim shown 80 in Fig. 10.

Fig. 12 is a section through a pendant trim similar to that illustrated in Figs. 10 and 11 but having means incorporated therein to prevent rattling of the pendant. 85

Fig. 13 is a partial section on line 13—13 of Fig. 12.

Fig. 14 is a perspective of a hand tool adapted to be used in attaching trimmings embodying the features of this invention. 90

Referring more particularly to the drawing and to the embodiment of this invention illustrated in Figs. 1 to 7, there is shown a trimming member for furniture in the form of a knob comprising a knob or handgrip portion 1 into which is secured by a press fit, a tubular post or stem 2, one end of which is splined as at 3 to increase its hold within the knob and the projecting end of which terminates in a pair of prongs 4 and a cup- 100

shaped anvil 7 for receiving and deflecting prongs 4. The usual escutcheon plate 6 is shown secured to the inner end of the knob.

The projecting end of the post is adapted to be received in the cup or sleeve-like anvil member 7 seated in a previously formed recess in the furniture. One end of the anvil is flanged outwardly as at 8, the latter flange having a pair of prongs 9 turned inwardly. The side wall of the cup is slotted as at 11 and the bottom thereof is concaved inwardly as at 12 to provide a wedge-like anvil portion which engages prongs 4, when the stem is forced inwardly, to spread the prongs outwardly through slots 11 and into the side walls of the recess formed in the furniture to receive the anvil as is clearly shown in Fig. 5. The flange 8 serves as a limiting means to prevent the anvil from receding into the wood regardless of how soft the wood may be, and the inturned prongs 9 secure the anvil within the recess in the furniture.

In Figs. 8 and 9, there is illustrated a ring type of trim comprising a plate 13 to which is pivotally secured a ring 14. The tubular post member 16 is secured to the other face of the plate and terminates in a pair of prongs 17 the post and prongs being similar to post 2 and prongs 4 previously described. This type of fitting is secured to the furniture in a manner similar to that previously described and which will not be repeated here.

In Figs. 10 to 12, there is illustrated a pendant type trim comprising a post or stem 18 to which is pivotally attached a pendant or hand grip 19 and the usual escutcheon plate 21. The post or stem portion is tubular, preferably being constructed of a single piece of sheet metal rolled to form a tubular stem one end of which terminates in a tongue bent upon itself to form a swivel loop or eye 22. The stem is further formed with a pair of lugs or stops 23 projecting laterally from its outer end and which serve to limit the swinging movement of the pendant to prevent the same from coming in contact with the front face of the furniture. The inner end of the tubular stem or post which is adapted to be received in a recess in the furniture terminates in a pair of prongs 24 adapted to be deflected into the furniture in the manner previously described by the use of an anvil 7.

In order to prevent the pendant 19 from rattling upon its pivot when attached to a piece of furniture subject to vibration, a spring 26 is coiled about the pivot pin of the pendant, one end 27 thereof (Fig. 13) being secured in the side of the pendant adjacent the pivot and the other end 28 lying upon the inside of the stem. The spring will thus tend to urge the pendant inwardly at all times against stops 23.

In Fig. 14 there is illustrated a tool which is particularly well adapted for use in attaching the foregoing furniture trimmings

to a piece of furniture. The tool comprises generally a handle 29 terminating in a shank 31 bored perpendicularly at one end to receive a set 32 positioned perpendicularly to the handle. One end 33 of the set is flattened in order that it may be struck squarely with a hammer, the other end is slotted as at 34 to provide a pair of prongs 36 and 37 the latter being longer than the former. The slot is of sufficient width to receive the eye 22 of the stem by means of which the stem may be driven into interlocking engagement with the anvil without spreading the eye. The shank is further provided with another bore perpendicular to the shank and to set 32. A punch 38 is secured in this latter bore, the punch being provided with a head 39 and a stem 41 having a pin 42 therethrough. The stem 41 and pin 42 are of proper size to be received in the cup-shaped anvil. The pin is also arranged parallel with the handle for reasons which will appear. It is obvious that the anvil may be set over the pin 41 with pin 42 extending through slots 11 and the anvil driven into the recess in the furniture by applying a hammer to the head 39. Due to the fact that pin 42 is parallel to the handle 29, the cup may be accurately aligned with the slots vertical thus insuring proper alignment of the pendant.

From the above description it follows that there is provided a trimming for furniture which may be rigidly and permanently secured to the furniture in such a manner to preclude removal therefrom and by means which do not detract from the ornamentation of the furniture nor projection through portions of the furniture. It is also apparent that in view of the fact that no screws or bolts are necessary the danger of splitting the furniture is eliminated. The formation of the anvil prevents the anvil from sinking into even relatively soft wood when the stem is driven thereagainst. Furthermore, the slotted anvil prevents any turning of the stem which might cause looseness and in combination with a particular tool for setting the same in place assures perfect alignment of the pendant and furthermore the slots prevent turning of the stem relatively to the anvil which further assures tightness of the trim. The trim can be attached to practically any thickness of furniture it merely being necessary to provide a recess of sufficient depth to receive the anvil.

It is obvious that the illustrated form of this invention is only one embodiment thereof and that many changes may be made in the structural details without departing from the spirit and scope of the invention as defined in the claims.

I claim:

1. A trimming for furniture comprising a stem adapted to enter a recess formed in the furniture, a cup-shaped anvil having an in-

clined bottom adapted to be received in said recess and shaped to deflect a portion of said stem into the side walls of the recess upon forcing the stem into said recess in engagement with said anvil, and means for limiting the inward movement of said anvil into the furniture.

2. A trimming for furniture comprising a stem adapted to enter a recess formed in the furniture and a cup-shaped anvil having an inclined bottom adapted to be received in said recess and shaped to deflect a portion of said stem into the side walls of the recess upon forcing the stem into said recess against said anvil, said anvil having an opening therethrough to permit passage of the deflected portion of the stem.

3. A trimming for furniture comprising a stem adapted to enter a recess formed in the furniture and a flanged cup-shaped anvil, the flange terminating in external prongs directed toward the bottom of the anvil, said

anvil having deflecting portions for engaging said stem and directing portions into the side walls of the recess upon forcing the stem into said recess into engagement with said anvil.

4. A trimming for furniture comprising a tubular stem terminating in prongs and adapted to enter a recess formed in the furniture and a cup-shaped anvil adapted to be positioned in said recess and to receive the end of said stem therein, said anvil having a flange for engaging the furniture to retain the anvil in position within said recess and having an outwardly inclined portion shaped to direct said prong outwardly upon engagement therewith into the side wall of the recess upon forcing the stem into said recess.

In witness of the foregoing I affix my signature.

EDWIN W. NORTH.
